UNITED STATES PATENT OFFICE

141,318

DESIGN FOR AN ELECTRIC IRONER

Walter A. Spear, Cincinnati, Ohio, assignor to
Victor Electric Products, Inc., Cincinnati, Ohio,
a corporation of Ohio

Application May 18, 1944, Serial No. 113,639

Term of patent 14 years

(Cl. D49—8)

To all whom it may concern:

Be it known that I, Walter A. Spear, a citizen of the United States, residing at Cincinnati, in the county of Hamilton and State of Ohio, have invented a new, original, and ornamental Design for Electric Ironers, of which the following is a specification, reference being had to the accompanying drawings, forming a part thereof.

Figure 1 is a front perspective view of an electric ironer, showing my new design.

Figure 2 is a rear view thereof.

Figure 3 is a top plane view.

Figure 4 is an end elevational view of the device looking in the direction of the power unit.

Figure 5 is another end elevational view looking in the direction of the ironing roll.

I claim:

The ornamental design for an electric ironer, as shown.

WATER A. SPEAR.
